UNITED STATES PATENT OFFICE.

RAYMOND MARSHALL, OF FRANKFORT, INDIANA.

STOVEPIPE ANCHOR AND LOCK.

1,333,625.

Specification of Letters Patent. Patented Mar. 16, 1920.

Application filed June 24, 1919. Serial No. 806,283.

To all whom it may concern:

Be it known that I, RAYMOND MARSHALL, a citizen of the United States, residing at Frankfort, in the county of Clinton, State 5 of Indiana, have invented certain new and useful Improvements in Stovepipe Anchors and Locks; and I do hereby declare the following to be a full, clear, and exact description of the invention, such as will enable 10 others skilled in the art to which it appertains to make and use the same.

This invention relates to stove pipe thimbles, and more especially it is an improved anchor and lock adapted for securing a stove 15 pipe section to the thimble so as to establish communication between the fire box of the stove and the chimney, and consequently the outside atmosphere.

It is the principal object of the invention 20 to produce an improved anchor and lock which will provide a secure and safe connection between the thimble and the stove pipe so that the latter will be prevented from coming loose or dropping out of its 25 place as usual; to obviate the necessity of employing suspending wires or the like, especially at the juncture of the pipe with the flue or chimney opening; to obviate the necessity of mutilating the wall around the 30 opening; to so improve the thimble and the lock as to obviate the possibility of escape of smoke and sparks thereby preventing fires, and to produce a novel construction of simple and economical production for securely connecting the stove pipe to the thimble. 35

With the above objects and others in view as will appear as the specification proceeds, the invention comprises certain novel combinations and arrangements of parts as will 40 be hereinafter more particularly pointed out and claimed.

Reference is had to the accompanying drawings forming a part of this application, 45 wherein like characters designate corresponding parts throughout the several views, in which—

Figure 1 is a front elevation partly broken away, showing the attachment in connection 50 with my improved safety stove pipe thimble.

Fig. 2 is an inside elevation,

Fig. 3 is a vertical sectional view taken on the line 3—3 of Fig. 1, and

Fig. 4 is an enlarged sectional detail on 55 the line 4—4 of Fig. 2, showing the use of the cams.

Referring to the drawings in detail, the numeral 10 designates the thimble proper formed from a short section of pipe having the usual circumscribing flange 11 extending outwardly from its rear end and adapted to hold the thimble within the flue opening in the chimney. The front end of the thimble has a flange 12 relatively wide as compared to the flange 11 which is relatively narrow, the flange 12 also circumscribing the thimble and itself having an inwardly extending head or flange 13 at its peripheral edge designed to abut the face of the wall around the opening into the flue. 70 The flange 12 is suitably attached to the front end of the thimble preferably by snugly fitting the thimble within the flange or fitting the flange on the thimble and slotting the thimble longitudinally as shown at 75 14 to provide a series of alternate spaced slots and alternate tongues 15 which are bent at right angles to the axis of the thimble against alternately inner and outer faces of the flange to hold it on the thimble. 80

The flange 12 is further provided with key hole slots 16 preferably four in number equidistantly spaced in a common circle concentric to the axis of the flange and the thimble itself. The circular portions 17 are 85 located at corresponding ends of the arcuate bodies of the slots. Outstanding from the rear face of the flange upon opposite sides of a slot are projections or cams 18 in the form of strips tapering toward the circular ends 90 17 and lying equidistantly apart throughout the lengths of the slots, but preferably extending beyond the other ends of said slots in convergent relation. The stove pipe which may be of any length, is designated 95 at 20 and this section of the pipe is provided with a flange 21 circumscribing its attaching end to fit against the flange 12 over the tongues 15 at the forward end of the thimble; and, the thimble and pipe section being 100 of the same diameter, the passages therethrough will accurately aline with each other. A collar 22 is fitted on the pipe section 20 and is preferably provided between it and the flange 21 with an asbestos or other 105 fire-proof packing 23 in the form of a ring, designed to prevent the escape of smoke, sparks, gases of combustion, etc. The collar 22 has around its outer portion a flat band 22' designed to fit snugly against the face 110 of the flange 12, both being of approximately the same diameter. The body of the

collar is of corrugated cross section formed by a series of concentric ribs, through the rib 25 of which openings are made in alignment with the openings 17 so as to receive 5 securing bolts 26 having enlarged heads 27, squared portions 28 adjacent to said heads and retaining nuts 29 engaged on the threaded portions thereof at the front face of the collar. Thus, with the bolts engaged 10 through the collar, the heads of the bolts may be passed through the circular openings 17 of the slots 16 and by turning the collar, the heads will be caused to ride up on the edges of the projections or cams 15 18 which are offset axially with respect to the flange 12, thus drawing the collar and the pipe section toward the thimble and said flange. As the squared portions 28 engage between said projections, the bolts are held 20 from turning and thus the nuts may be tightened to effect a very close union. In addition, a plate or disk may be provided to close the opening of the thimble when the stove and pipe section are taken down during 25 the summer months, said disk being fitted between the collar and the flange 12 and having openings alining with the aforesaid openings in the collar and flange for receiving the bolts therethrough.

30 What is claimed is:

1. The combination with a stove pipe section having a flanged end; of a fire-proof packing ring on said pipe section, a collar on said pipe section over the ring, a thimble 35 having a flanged front end, and cam means connecting the collar and thimble flange to lock the two together.

2. A stove pipe thimble, a flange on the front end of the thimble having arcuate 40 slots therethrough, cams on the rear face of the flange adjacent the slots, a collar, and connecting means engaging the collar and passing through the slots for drawing the collar toward the flange by engagement with 45 the cams.

3. The combination with a stove pipe section having a flanged end; a fire-proof packing ring on said pipe section, and a collar on said pipe section over the ring; of a thimble, a flange at its front end having equidistant slots concentric to the thimble, cam 50 projections at the edges of the slots, and bolts through the collar and slots engaging the edges of the cams to draw the collar, 55 packing, and pipe section toward the flange upon the collar being rotated with the bolts.

4. The combination with a thimble to enter a stove pipe opening, a radial flange at its front end having an edge flange extending 60 axially, said radial flange having spaced arcuate keyhole slots therethrough, and cams

projecting from the rear face of this flange adjacent the slots; of a collar having openings alining with said slots, bolts engageable through said openings and slots, their heads designed to pass through the enlarged portions of the slots and to draw said collar toward the flange by rotating the collar to cause movement of the heads along the cams, and means for preventing turning of the 70 bolts.

5. The combination with a thimble to enter a stove pipe opening, a radial flange at its front end having spaced arcuate keyhole slots therethrough, cams projecting from the 75 rear face of the flange adjacent the slots, a collar having openings alining with said slots, and bolts through said openings and slots, the head portions being designed to pass through the enlarged portions of the 80 slots and to draw said collar toward the flange by rotating the collar to cause movement of the heads along the cams; of a pipe section having a flange retained by said collar, and a packing between the collar and 85 the flange of the pipe section.

6. The combination with a stove pipe section having a flanged end, and a ribbed collar engaged at its inner edge on said pipe section, and having a flat band around its 90 outer edge; of a thimble, a flange at its front end having equidistant keyhole slots concentric to the thimble and with their enlarged portions at corresponding ends, cam projections along the edges of the bodies of the 95 slots beyond the enlarged portions and tapered toward the latter, bolts through the collar between its edges and having enlarged heads and adjacent squared portions, the heads being designed to ride on the cams 100 as the collar is revolved on the thimble and the squared portions engaging between the cams to hold the bolts against turning, and nuts engaged on the bolts against said collar.

7. The combination with a stove pipe section having a flanged end; of a thimble comprising a short section of tubing having a flanged rear end, a relatively wide flange around its front end, said front end having spaced cuts producing tongues and said 110 tongues being bent to engage opposite faces of the wide flange whereby the same is retained on the tube section, a collar designed to receive said stove pipe section, and means detachably connecting the collar and said 115 front flange.

In testimony whereof, I affix my signature, in the presence of two witnesses.

RAYMOND MARSHALL.
